UNITED STATES PATENT OFFICE.

JAMES BOYN, OF CHICAGO, ILLINOIS.

SCREW.

1,110,250.

Specification of Letters Patent.

Patented Sept. 8, 1914.

Application filed May 20, 1914. Serial No. 839,851.

To all whom it may concern:

Be it known that I, JAMES BOYN, a citizen of the United States, residing at Chicago, in the county of Cook and State of Illinois, have invented new and useful Improvements 5 in Screws, of which the following is a specification.

This invention relates to screws and in particular to those commonly known as 10 "stage screws." The primary object being to provide a device of this character which consists of a body for permanent use and means for securing an ordinary wood screw thereto, in order that the screw may be 15 replaced when worn or broken without having to discard the body of the screw.

A further object of the invention is to provide a screw of this class whose body portion is constructed in such a manner that 20 it may be used as a cork screw, a screw driver, a wrench, and in various other capacities.

The invention consists in the features of construction, combination, and arrangement 25 of parts, hereinafter fully described and claimed, reference being had to the accompanying drawing, in which:

Figure 1 is a side elevation of the body of the device, showing an ordinary wood 30 screw connected therewith; Fig. 2 is a longitudinal sectional view on line 2—2 of Fig. 1; Fig. 3 is a transverse sectional view on line 3—3 of Fig. 2; Fig. 4 is a side elevation of a cork-screw adapted to be applied 35 to the body; Fig. 5 is a similar view of a screw-driver which is adapted for the same use; Fig. 6 is a longitudinal sectional view through a portion of a modified form of screw body; and, Fig. 7 is a longitudinal sec- 40 tional view on line 7—7 of Fig. 6.

In the drawings, the numeral 1 designates the body portion of the device, which is provided at its upper end with oppositely extending, lateral wings 2 which permit the 45 body to be grasped securely when operating the same. The body is provided medially with a longitudinal slot 3 opening through the opposite side faces thereof. A longitudinal opening 4 is provided in the lower end 50 of the body in communication with the slot for the reception of the shank of an ordinary wood screw, such as is indicated by the numeral 5. The threaded portion 6 of the screw is adapted to project outwardly from 55 the body, whereas its head 7 is countersunk within the inner end of the body opening 4.

Longitudinal guide grooves 8 are provided in the side walls of the body slot 3 and extend through the side walls of a second opening 9 which is provided in the upper end of the body in communication with its slot. A flat securing member 10 is adapted to be mounted within the body with its side edges slidably engaged within the grooves 8. The inner end of the securing member 60 is provided with a beveled edge 11 for engagement within the head kerf of the screw 5, whereby the latter will be held against rotation in its connection with the body. An operating screw 12 is rotatably mounted 65 within the body opening 9 with its head 13 disposed exteriorly thereof and with its inner end engaged within a socket 14 which is provided in the upper end of the securing member. The screw 12 extends through a 70 threaded nut 15, which is mounted within the upper end of the body slot 3 and is held against rotation owing to its snug fit within the socket. Instead of providing the nut 15, the screw body may be modified, as 75 shown particularly in Fig. 6, by providing a threaded opening in the upper end of the body in communication with the slot for the reception of the screw.

The body slot 3 is constructed of such 80 length as to permit the introduction of the replaceable wood screw into the same when mounting the screw within the opening 4. When it is desired to remove the securing member for the purpose of repair or to 85 clean the same, the operating screw is withdrawn, whereupon the securing member 90 may be removed through the body opening 13 and the extensions of the grooves 8.

In order that the body of the screw may 95 be used also as a wrench for turning certain kinds of tools, non-circular openings 16 are provided in its wings. A screw driver extension 17 also is formed upon the outer end 100 of one wing, and a tack-pulling extension 18 is formed upon the opposite wing, in order that the body may be used in the further capacities of screw driver and tack puller. In Fig. 4, a cork-screw is shown constructed for use in the body of the device, and in 105 Fig. 5 a screw driver is shown constructed for like use.

From the foregoing description, taken in connection with the accompanying drawings, it should be apparent that I have provided 110 a stage screw which is adapted to be used for a long period of time, it being

necessary merely to replace the wood-screws, used in connection therewith, as they become worn or otherwise damaged. The body of the device is also constructed so that it may be used for several different purposes in stage work.

What is claimed is:

1. In a device of the class described, the combination with a rotatable element having a head, of a body having an opening therein for the reception of the said element, a securing member mounted movably within the body and having one edge adapted for engagement with the head to secure the element against movement within the body, the said securing member being longitudinally movable with respect to the said element, and an operating screw adjustably mounted within the body in axial alinement with the securing member for engagement with the end thereof opposite to the edge engaged with the said element.
2. In a device of the class described, the

combination with a rotatable element having a head, of a body provided with an elongated slot and with an opening therein in registration with one end of the slot for the reception of the said element, the side walls of the said slot being provided with longitudinal grooves, and a securing member mounted within the body slot with its side edges slidably engaged within the grooves, one end of the securing member being adapted for engagement with the head of the said element to secure the same against movement within the body, the body being provided further with an opening in communication with the opposite end of the said slot for passage of the securing member therethrough.

In testimony whereof I affix my signature in presence of two witnesses.

JAMES BOYN.
